UNITED STATES PATENT OFFICE.

CARL SCHNEIDER, OF JERSEY CITY, NEW JERSEY, ASSIGNOR TO INTERNATIONAL ELECTRICAL MANUFACTURING COMPANY, OF NEW YORK, N. Y., A CORPORATION OF NEW YORK.

COMBINATION INSTRUMENT.

No. 870,851.

Specification of Letters Patent.

Patented Nov. 12, 1907.

Application filed November 4, 1905. Serial No. 285,810.

To all whom it may concern:

Be it known that I, CARL SCHNEIDER, a citizen of the United States, and resident of Jersey City, in the county of Hudson and State of New Jersey, have invented a new and useful Improvement in Combination Instruments, of which the following is a specification.

The object of this invention is to provide a novel combination instrument in which will be combined the following useful instruments; dividers, pencil compasses and pen compasses.

A further object is to provide certain detail improvements in the several parts whereby the delicate parts of the same may be protected when the instrument is not in use.

A further object is to provide an instrument of the above character with a removable eraser arranged in a novel manner.

In the accompanying drawings, Figure 1 represents the instrument in side elevation closed, the needle point on one branch and the pencil point on the other branch being extended into position for use, Fig. 2 is a similar view with the instrument open as in use, Fig. 3 is an edge view of the same, Fig. 4 is a longitudinal central section through the instrument in open position when used as a pen compass, Fig. 5 is a fragmentary section showing the needle points extended from both branches for rendering the instrument capable of use as a pair of dividers, Fig. 6 is a similar view with the two needle points withdrawn for the purpose of protecting them, Fig. 7 is a detail sectional view of the pen portion of one of the branches showing the pen points spread apart by the sliding adjuster, and Fig. 8 is a detail sectional view of the pencil portion of one of the branches showing a modified arrangement for holding the pencil in its position without causing the needle point to bite into or score the same.

The two branches of the instrument are denoted by 1 and 2. These branches are hinged together by the pivot pin 3, on which pivot pin is mounted the handle 4.

The branch 2 of the instrument is of U-shaped form in cross section and at its lower end it is provided with a needle point 5 which may be moved out beyond the end of the branch or back into the interior of the same as desired, the device herein shown for accomplishing this result comprising a spring plate 6 having a pin 7 fastened to the needle point 5, which pin is fitted to slide in a longitudinal groove 8 in the said branch.

50 The plate 6 exerts a sufficient tension on the needle point 5 to cause it to retain its extended or withdrawn position as may be desired.

The branch 1 of the instrument comprises an upper portion and a lower portion 9 pivoted at 10 to the upper portion, the upper portion consisting of two side plates

11 and 12 between which the lower portion 9 is fitted to swing. This lower portion 9 of the branch is provided with a pencil arm 13 and a pen arm 14.

The pencil arm 13 is provided with a needle point 15 and a socket 16 in which a pencil point 17 may be clamped in its extended or withdrawn position by the needle point. This needle point 15 is provided with a cam surface 18 for accomplishing this result. This needle point 15 is further provided with a tongue 19 which is fitted to slide in an elongated slot 20 in the pencil arm 13.

The pen arm 14 is extended to form one blade of the pen and the other blade 21 of the pen is so attached to the pen arm as to leave its point normally pressed against the point of the other blade.

A sliding adjuster 22 is provided with a cam 23 at one end and a handle 24 at its other end. This handle 24 is formed by bending the strip which forms the adjuster back upon itself so as to grip the inner end of the pen blade 21. As the adjuster is moved downwardly, its cam 23 will gradually force the blades 14 and 21 apart thus insuring the formation of lines of varying widths and, at the same time, providing a pen which can be folded between and protected by the two side plates 11 and 12 of the branch 1 of the instrument.

The two branches of the instrument are so arranged that the branch 1 may be folded within the branch 2 when the instrument is out of use. The branch 2 is provided with a recess 25 in one of its sides for receiving the head 26 of the pivot screw 10 which pivots the lower portion 9 of the branch to the upper portion.

The handle 4 of the instrument may be provided with an eraser 27.

When the instrument is folded and not in use, the needle points and pencil may be withdrawn as shown in Fig. 6 for protecting the same.

It will be seen that this combination instrument is so constructed that the same may be used as an ordinary pencil or as dividers, as shown in Fig. 5, or as a pencil compass as shown in Fig. 1 or as a pen compass as shown in Fig. 4.

In Fig. 8 I have shown a modified form in which a presser plate 28 is interposed between the pencil point 17 and the needle point 15 so that the needle point will not be caused to bite into the lead and thus tend to score or break the same. Furthermore, this presser plate 28 serves to permit a frictional grip on the lead over a more extended surface. This presser plate may be held in position by bending its inner end around the pivot screw 10.

105 What I claim is:—

1. A combination instrument having two branches hinged together, both of the said branches having longitudinally adjustable needle points arranged to be extended into and withdrawn from operative position, one of the said needle

110

points having a cam surface and one of the said branches having a longitudinally adjustable pencil arranged to be clamped in its extended or withdrawn position by the needle point having the cam surface.

- 5 2. A combination instrument having two branches hinged together, both of the branches having longitudinally adjustable needle points arranged to be extended into and withdrawn from operative position, one of the said needle points having a cam surface and one of the branches being
10 further provided with a longitudinally adjustable pencil, and a presser plate controlled by the needle point having the cam surface, for clamping and releasing the pencil.
15 3. A combination instrument having two branches hinged together, one of the said branches having a spring pressed longitudinally adjustable needle point arranged to be ex-

tended into and withdrawn from operative position and the other of said branches comprising an upper portion and a lower portion pivoted to the upper portion, said lower portion having one of its arms provided with a pen and its other arm provided with a longitudinally adjustable pencil and a longitudinally adjustable needle point having a cam surface, for clamping the pencil in its extended or withdrawn position. 20

In testimony, that I claim the foregoing as my invention, I have signed my name in presence of two witnesses, 25 this 2nd day of November 1905.

CARL SCHNEIDER.
